(57) **CLAIM**

We claim the ornamental design for a pregnancy tester, as shown and described.

DESCRIPTION

FIG. 1 is a perspective view of a pregnancy tester;
FIG. 2 is a top view thereof;
FIG. 3 is a side view with the opposite side being a mirror image thereof;
FIG. 4 is a front view thereof;
FIG. 5 is a back view thereof;
FIG. 6 is a bottom view thereof; and,
FIG. 7 is an alternate view showing the pregnancy tester without the raised unclaimed ridges.
The broken lines showing raised ridges and a central oval display area, as well as a center line, as seen in the drawings are for illustrative purposes only and form no part of the claimed design.
